SILENT TUNING RADIO RECEIVER

Hulbert C. Tittle, Eggertsville, N. Y., assignor to
 Colonial Radio Corporation, Buffalo, N. Y., a
 corporation of New York

Application September 15, 1937, Serial No. 163,947

7 Claims. (Cl. 250—20)

This invention relates to improved so-called silent tuning systems for radio receivers, i. e., tuning systems in which the receiver is so constructed and arranged as to require a signal of predetermined strength to cause response, and which may be so adjusted that signals of less than such strength, atmospheric, man-made static, etc., will not produce a response. With such a receiver, it is possible to tune from one station to another having the predetermined strength, and have the receiver quiet during the time of transition between stations, whereas, the usual type receiver embodying so-called automatic volume control is most sensitive when no signal is being received, and is likely to be very noisy when being tuned from one station to another.

The usual type silent-tuning receiver, however, is open to the objection that in order to keep the receiver in responsive condition, the signal strength must be at all times equal to or greater than that required to cause initial operation. This is particularly troublesome in automobile receivers, in which the signal strength is likely to fluctuate as the vehicle travels, even in the case of strong signals, and reception may thereby be interrupted from time to time.

It is an object of this invention to provide a receiver of the so-called silent tuning type, which is relatively free from the drawbacks heretofore associated with such receivers.

More particularly, it is an object of this invention to provide a receiver in which a predetermined incoming signal strength is required to cause response of the receiver, but which when once set into operation by a signal of such strength, will nevertheless continue to respond to such station even if the strength of the signal received should fall far below the level required to cause initial response.

It is a further object of this invention to provide a silent tuning receiver embodying automatic volume control, which requires a signal of predetermined strength to cause it to be responsive, but which, once rendered responsive by a signal of such strength, will thereafter operate like an automatic volume control receiver, as long as the station continues to be received, even though the strength of the signal received drops far below that required to produce initial response of the receiver.

It is a further object of this invention to provide a receiver which requires an incoming signal of predetermined strength to produce initial re-

sponse, and which, once rendered responsive by a signal of such strength, will continue to respond to such signal even though it should drop far below the strength required to produce initial response, but which will cease to respond to the incoming signal if it falls below a predetermined minimum strength level. 5

It is a further object of this invention to provide a receiver which requires an incoming signal of predetermined strength to produce initial response, and which, once rendered responsive by a signal of such strength, will continue to respond to such signal even though it should drop far below the strength required to produce initial response, and which will cease to respond to the incoming signal if it falls below a predetermined minimum strength level, and thereafter will be 10 unresponsive to signals having less than the predetermined strength required for initial response. 15

Still other objects and advantages of my invention will be apparent from the specification. 20

The features of novelty which I believe to be characteristic of my invention are set forth with particularity in the specification. My invention itself, however, both as to its fundamental principles and as to its particular embodiments, will best be understood by reference to the specification and accompanying drawing, in which: 25

Figure 1 is a schematic circuit diagram of one form of circuit operating according to my invention, and 30

Fig. 2 is a curve illustrating the operation of my invention.

The operation of a receiver according to my invention is somewhat analogous to the well known hysteresis effect. Referring now more particularly to Fig. 2, the abscissae represent the strength of the incoming signal in micro-volts, while the ordinates represent the strength of the signal output from the receiver in volts. The direction to be followed around the loop is shown by the arrows. 35 40

From this it will be seen that so long as the incoming signal is less than 1,000 microvolts, no signal output will be produced; i. e., the receiver will be unresponsive to incoming signals. Once the strength of incoming signals reaches 1,000 microvolts, however, the signal output of the receiver increases extremely rapidly to the value 50 indicated, in the neighborhood of 1.0 volt.

If for any reason the strength of the incoming signal should now decrease, the receiver will continue to respond, even though the strength of the signal should drop below that required to pro- 55

duce initial response of the receiver. This is indicated by the downwardly sloping dotted line portion of the curve, and the receiver will continue to respond, although with somewhat diminished strength, until the incoming signal falls as low as 10 microvolts.

At this point, which corresponds generally to the minimum strength of signal for which satisfactory operation is possible, any further decrease in incoming signal strength causes the receiver to cease to respond, as is indicated by the drop of the dotted line to zero. Thereafter, the receiver will not respond until the incoming signal strength reaches the value necessary to cause initial response; i. e., 1,000 microvolts.

Referring now to Fig. 1, I have shown so much of the circuits of a super-heterodyne receiver employing my invention as is necessary to an understanding of one preferred embodiment thereof. In this figure, the incoming signals may be received upon an antenna of any suitable type, not shown, and impressed upon the primary 50a of the high frequency transformer 50, and thus upon the secondary 50b thereof.

25 The coil 50b, tuned by condenser 51 forms a tuned circuit tuned to the frequency of the incoming signals, which may then be amplified without change of frequency in tube 52, herein shown as a pentode embodying heater 52a, cathode 52b, control grid 52c, screen 52d, suppressor 52e, and anode 52f. The cathode may be connected to ground through self-biasing resistor 54 shunted by a by-pass condenser (not numbered) and the common point of coil 50b and condenser 51 may be connected to the control grid, and the opposite terminals of each may be grounded, condenser 51 directly, and coil 50b through by-pass condenser 53. The other electrodes of tube 52 may be connected as well known 40 in the art.

The anode 52f may be connected to a suitable positive point such as to the positive side of the power supply, herein illustrated as a rectifier and filter system for operating from alternating current, well known in the art, and not described in detail.

Included in the plate or anode circuit of anode 52f there may be provided the primary winding 55a of the radio frequency transformer 55, the 50 secondary winding 55b of which may form, with variable condenser 56, the tuned input circuit to the next tube 57, which may be, and is herein illustrated as a penta-grid converter.

55 Tube 57 may comprise heater 57a, cathode 57b, various electrodes termed "grids" (although some of them may not be in conventional grid form) 57c, 57d, 57e, 57f, 57g, and anode or plate 57h. These grids may be interconnected in the well known manner to cause the tube to generate 60 heterodyning oscillations of the desired frequency and to combine these oscillations with the incoming signal within the tube, the signals being impressed upon control grid 57c, from condenser 56.

65 Condenser 56 may have one side grounded, and the free end of coil 55b may be connected to the grid return line, and may be separated from the return connection of grid 52c by resistance 74. Cathode 57b may be connected to ground through 70 self-biasing resistance, shunted by a by-pass condenser. The plate or anode 57h may be connected through the primary winding 59a of intermediate frequency transformer 59 to a suitable positive point on the power supply.

75 As will be understood the action of the tube is

to deliver to transformer 59 currents of beat or intermediate frequency, and it will be understood that the heterodyning oscillations may be generated in a separate tube, if desired, and combined with the signals in any suitable manner. For this reason the specific connections of the remaining electrodes of the tube 57 are omitted for simplicity, they being well known in the art.

The intermediate frequency signals in the secondary 59b of the intermediate frequency transformer 59, both windings of which may be tuned by trimmer or tuning condensers may be impressed upon the control electrode 60c of tube 60, which may still further amplify them at intermediate frequency. The cathode 60b may be 15 connected to ground through a self-biasing resistance shunted by a by-pass condenser as before.

The return side of coil 59b may be connected to the grid return line, but separated from the connection of coil 55b by resistance 75, and both latter grid returns may be by-passed to ground through condensers 79 and 80.

The plate or anode 60f may be connected through primary 61a of intermediate frequency 25 transformer 61 to a suitable positive point on the power supply.

One terminal of the secondary 61b may be connected to the diode anode 62c of the tube 62, herein shown as a diode-triode, and comprising 30 heater 62a, cathode 62b, diode anode 62c, control grid 62d, and main or triode anode 62e. The output from the triode anode 62e may be audio frequency currents only, which may be led to additional amplifying stages, well known in the 35 art, and not shown, and thence to a signal indicator, for instance a loud speaker, likewise not shown.

The opposite terminal of secondary 61b may be connected through condenser 73, forming by pass 40 for radio frequency. A direct current path from diode anode 62c to cathode 62b may be provided by resistance 72 and resistance 67 in series to ground, thence to cathode 62b, which may be directly grounded.

Resistance 67 may be shunted by condenser 69 and resistance 68 in series, and audio frequency currents may be supplied to grid 62d by a connection through condenser 70 to a variable point on resistance 68. Grid 62d may be returned to any suitable point through resistance 71, as is well known in the art.

Control tube 63 may be provided, which may be of any suitable type, herein shown as a diode triode, having heater 63a, cathode 63b, diode 55 anode 63c, control grid 63d, and triode anode 63e. Triode anode 63e may be connected to the common point of resistance 67 and condenser 69, and through resistance 76 to the return side of coil 59b.

Diode anode 63c may be connected to cathode 63b through resistances 64 and 65 in series, the latter being shunted by by-pass condenser 66, and its point of connection to resistance 64 may be connected through condenser 81 65 to anode 60f. Cathode 63b may be connected to the negative side of the power supply, and through variable tap 78 on resistance 77 to ground.

The operation of this circuit is as follows: for 70 no signal, plate current flowing from cathode to triode anode of control tube 63 maintains the triode anode 63e negative with respect to ground, the space current path being from cathode 63b to tap 78, resistance 77 to ground, through resist- 75

ance 67 to anode 63e. Since grids 52c, 57c, 60c, and diode anode 62c are all connected to triode anode 63e, negative potential is applied to said electrodes also.

5 It will be clear that by regulating the strength of this bias voltage, as by adjusting the position of tap 78, sufficient bias may be maintained on the tubes 52, 57, 60 and 62, to prevent any response of the receiver except to signals of sufficient strength to override the bias, and which strength may be predetermined, and adjusted for.

If a signal exceeding this strength is received, current will begin to flow in the said tubes, and intermediate frequency current appears in the output circuit of tube 60. Through condenser 91, this or a portion of it is applied to the diode anode of control tube 63, and therein rectified. Rectified current flows from cathode 63b through resistance 65, and resistance 64 to diode anode 20 63c, thereby making control electrode 63d negative with respect to cathode 63b.

This causes the plate current in tube 63 to be cut off, and permits the grids 52c, 57c, 60c, and diode anode 62c to assume a potential determined by the rectified signal current of diode anode 62c, flowing through its space current path already traced, and which causes grids 52c, 57c, and 60c, to become more negative with respect to their cathodes, thus tending to maintain a constant output from the diode portion of tube 62, regardless of the strength of the incoming signal, provided its strength lies between the limits at which blocking and unblocking occur.

As the signal strength decreases, the receiver 25 will nevertheless continue to respond, until the signal falls to a strength far below that required to unblock the receiver initially. For instance, if 1000 microvolts is required to unblock the receiver and make it responsive, the receiver will 40 continue to operate until the signal fades to 10 microvolts, for example.

Should the signal strength fall below this value, the rectified intermediate frequency currents flowing through resistance 65 will no longer 45 be sufficient to keep plate current from flowing in the triode anode circuit of tube 63, and flow of this current will make anode 63e negative with respect to ground, and apply negative bias to grids 52c, 57c, 60c, and diode anode 62c, returning to receiver to blocked, or no signal condition.

The action is a sharp snapping over from blocked to unblocked condition, and vice versa, and in the hysteresis effect, i. e., the requirement of a strong signal to cause unblocking, but once 55 unblocked, the fading of the signal to a very much lower value to cause blocking to occur.

While I have shown and described certain preferred embodiments of our invention, it will be understood that modifications and changes may 60 be made without departing from the spirit and scope of my invention.

I claim:

1. In radio receiving apparatus, in combination, a plurality of amplifier tubes connected for progressive amplification of incoming signals, a thermionic rectifier supplied by said amplifier tubes, a connection between said rectifier and the control electrode of at least one of said amplifier tubes for applying rectified voltage thereto 65 as a bias to regulate the gain inversely in accordance with the strength of incoming signals, a control tube supplied by the output of one of said amplifier tubes, an impedance in the plate circuit of said control tube whereby the plate potential thereof decreases with increase of space 70 75

current in said tube, and a connection from said plate to the control electrode of at least one of said amplifier tubes, and to said rectifier for applying a blocking bias thereto.

2. In radio receiving apparatus, in combination, at least one amplifier tube connected for amplification of incoming signals at super-audible frequency, a thermionic rectifier supplied by said amplifier tube, a connection between said rectifier and a control electrode of said amplifier tube for applying rectified voltage thereto as a bias to regulate the gain thereof inversely with the strength of incoming signals, a control tube comprising an anode, a cathode and a control electrode, a connection from said control electrode of said control tube to the output circuit of said amplifier tube, an impedance in the plate circuit of said control tube whereby the plate potential thereof decreases with increase of space current in said control tube, and a connection from said anode to said rectifier for applying a blocking bias thereto.

3. In radio receiving apparatus, in combination, at least one amplifier tube connected for amplification of incoming signals at super-audible frequency, a thermionic rectifier supplied by said amplifier tube, a connection between said rectifier and a control electrode of said amplifier tube for applying rectified voltage thereto as a bias to regulate the gain thereof inversely with the strength of incoming signals, a control tube comprising an anode, a cathode and a control electrode, a connection from said control electrode of said control tube to the output circuit of said amplifier tube, an impedance in the plate circuit of said control tube whereby the plate potential thereof decreases with increase of space current in said control tube, and a connection from said anode to a control electrode of said amplifier tube and to said rectifier tube for applying a blocking bias thereto.

4. In radio receiving apparatus, in combination, at least one amplifier tube connected for amplification of incoming signals at super-audible frequency, a thermionic rectifier supplied by said amplifier tube, a connection between said rectifier and a control electrode of said amplifier tube for applying rectified voltage thereto as a bias to regulate the gain thereof inversely with the strength of incoming signals, an additional rectifying element, a connection between said additional rectifying element and the output of said amplifier, a control element comprising an anode, a cathode, and a control electrode, means for applying voltage from said additional rectifier element to said control element in a manner to cause cut off of plate current in said control element, and a connection from said anode to a control electrode of said amplifier tube to cause blocking and unblocking of said amplifier at different values of incoming signal respectively.

5. In radio receiving apparatus, in combination, at least one amplifier tube connected for amplification of incoming signals at super-audible frequency, a rectifier supplied by said amplifier tube, a connection between said rectifier and a control electrode of said amplifier tube for applying rectified voltage thereto as a bias to regulate the gain thereof inversely with the strength of incoming signals, an additional rectifying element having an impedance in circuit therewith, a connection between said additional rectifying element and the output of said amplifier, said connection including said impedance, a control element comprising an anode, a cathode 65 70 75

and a control electrode, the input circuit of said control element including at least a portion of said impedance, and a connection from said anode to said first rectifier to cause blocking and unblocking of said rectifier at different values of incoming signal.

6. In radio receiving apparatus, in combination, at least one amplifier tube connected for amplification of incoming signals at super-audible frequency, a rectifier supplied by said amplifier tube, a connection between said rectifier and a control electrode of said amplifier tube for applying rectified voltage thereto as a bias to regulate the gain thereof inversely with the strength of incoming signals, an additional rectifying element having an impedance in circuit therewith, a connection between said additional rectifying element and the output of said amplifier, said connection including said impedance, 10 a control element comprising an anode, a cathode, and a control electrode, the input circuit of said control element including at least a portion of said impedance, and a connection from said anode to a control electrode of said amplifier

tube to cause blocking and unblocking of said amplifier at different values of incoming signal.

7. In radio receiving apparatus, in combination, at least one amplifier tube connected for amplification of incoming signals at super-audible frequency, a rectifier supplied by said amplifier tube, a connection between said rectifier and a control electrode of said amplifier tube for applying rectified voltage thereto as a bias to regulate the gain thereof inversely with the strength 5 of incoming signals, an additional rectifying element having an impedance in circuit therewith, a connection between said additional rectifying element and the output of said amplifier, said connection including said impedance, a control 15 element comprising an anode, a cathode and a control electrode, the input circuit of said control element including at least a portion of said impedance, and a connection from said anode to a control electrode of said amplifier tube and 20 to said first rectifier to cause blocking and unblocking of said amplifier and rectifier at different values of incoming signal.

HULBURT C. TITTLE.
